[57] CLAIM

The ornamental design for an acoustical panel, as shown and described.

DESCRIPTION

FIG. 1 is a front, top and right side perspective view of the acoustical panel of the invention;

FIG. 2 is a top plan view thereof;

FIG. 3 is an end elevation view thereof with the opposite end being substantially identical;

FIG. 4 is a bottom plan view thereof;

FIG. 5 is a right side view thereof with the opposite side being substantially identical; and,

FIG. 6 is an enlarged plan view of a section of the pattern shown on the panel of FIG. 1.

The pattern shown in FIGS. 1 through 4, is repetitive throughout the top, bottom, and end surfaces of the acoustical panel.

FIG. 1

FIG. 2

FIG. 3

FIG. 4**FIG. 5**

FIG. 6
